COMMODITY ACCOMMODATION AND VENDING RACK

Sylvan N. Goldman, Oklahoma City, Okla.

Application December 22, 1937, Serial No. 181,228

4 Claims. (Cl. 211—74)

The invention disclosed in the accompanying drawings, and about to be described and claimed, relates to what may be broadly referred to as a commodity accommodation and vending rack. Visualized in greater particularity, however, it relates to a relatively small portable style accessory, expressly but not necessarily, adapted for use in grocery stores and similar establishments, its primary purpose being to facilitate self-service handling of bottled milk and equivalent articles.

In reducing to practice the preferred embodiment of the invention I have found it expedient and practicable to employ an open-work frame structure, lightweight but durable, said structure being characterized in particular by an inclined chute which adequately supports the bottles and permits the same to feed by gravity toward the discharge end for expeditious removal by the customer.

A further object of the invention is to provide a collapsible or foldable frame embodying transverse end members and longitudinal frame members, the parts being hingedly adjoined together and maintained, when in use, in non-foldable position by a detachable insert, which latter part constitutes the runway or chute for the contents of the rack.

Such other specific equipments as are embodied in the assembly will become more readily apparent from the following description and drawings.

In the drawings, wherein like numbers designate like parts throughout the views:

Figure 1 is a side elevational view showing the rack set up for use.

Figure 2 is a top plan view of the same.

Figure 3 is a transverse vertical or cross sectional view taken approximately on the plane of the line 3—3 of Figure 2.

Figure 4 is a fragmentary top plan view showing the use of a double acting clip employed for assembling two of the racks in side by side relationship, when it is desired to employ the same in battery combinations.

Figure 5 is a sectional view showing the means utilized at the front for employing the racks in pairs whenever necessary or desired.

Figure 6 is a view showing, in perspective, one of the end members and illustrating how a portion of the flange is bent to serve as a detent to facilitate maintaining the frame folded.

Figure 7 is a detail view of the two-way or double acting rack assembling clip.

Reference being had now to Figures 1 and 2 in particular, it will be observed, as before indicated, that the foldable or collapsible frame

means forming the open-work rack is essentially constructed from the use of a pair of duplicate longitudinal side frames or units 8 and connecting transverse front and rear units 9 and 10. Each side frame is preferably formed from wire of appropriate strength and includes a horizontal bottom bar 11, an inclined top rail 12 and vertical front and rear connecting members 13 and 14. The end members 9 and 10 each include sheet metal plates 15 of appropriate dimensions. The opposite ends of the plates are rolled upon themselves to form tubular assembling and hinging elements 16. The elements 16 surround the end posts or hinge members 13 and 14 whereby to foldably assemble the respective units. Attention is called now to the laterally bent bottom flange 17 on the front end wall. This is directed laterally inward and at its center has upstruck tongues 18 which constitute detents for the adjacent end of the channel-shaped bottle supporting and frame retaining chute 19. This part 19 is of a length commensurate with the complete frame and occupies an inclined position, the opposite end thereof being removably snapped into an outwardly pressed keeper seat 20 formed horizontally in the upper portion of the rear wall 21 as brought out to advantage in Figure 2. These coacting features 18 and 20 serve to effectively maintain the detachable channel 19 in place. In turn the part 19 maintains the frame distended or in rack-forming relationship.

Considering the laterally directed flange on the lower portion of the wall 21 (see Figure 6) it will be observed that one end thereof is bent or deflected as at 22 to form what may be conveniently called a retention lip. This lip frictionally engages the adjacent frame member 8 and facilitates maintaining the two frames parallel while inserting and removing the slanting chute 19.

I now call attention to additional auxiliary accessories. For example, a suitable suspension hook 23 may be provided on the end wall 10 whereby to permit the device to be hung in an ice-box or similar place and to dispose it conveniently in a horizontal position, to expedite removal of the products by the passing customer.

I also call attention to the double acting clip 24. This comprises a suitable metal plate 25 having bent sheaths or hooks 26 at opposite ends adapted to snap over adjacent end members 10, when two of the racks are positioned in side-by-side relationship as somewhat diagrammatically illustrated in Figure 4. In this figure it

was considered not necessary to show the whole rack since the principle of assembling is quite evident. It is perhaps, novel, however, to employ a plurality of racks and to detachably assemble and join the same together by this double hook clip 24. The hook alone does not serve to securely adjoin the two racks. Thus it will be seen that each rack is provided on one of the frame members with an auxiliary clip 27. This 10 is in the form of a ring surrounding the bottom bar 11. It is provided with an outstanding bendable end portion 28 which can be bent into hook form as shown in Figure 5. Thus, with the clip 24 at one end and the auxiliary bendable clip 15 means 27 and 28 at the opposite end, the racks 15 may be arranged in convenient pairs. This is merely for augmented display and convenience of use.

The features denoted by the numeral 29 at 20 the front in Figure 1 are simply bendable tongues or ears such as may be employed to hold in place a price tag, trade-marking card or the like (not shown).

In use, the following features will be found 25 praiseworthy.

The bottle rack is placed inside of grocery dairy boxes, milk bottles are placed on the slide and when a customer in a self-service store removes one bottle from the front the balance of 30 the bottles slide forward, thereby keeping the milk bottles constantly brought to the front of the box so shoppers do not have to reach far back into the box to get their bottles of merchandise.

Another advantage is that when refilling this 35 slide the bottles are placed in the back of the merchandise already there. This keeps the old merchandise always pushed forward and it is moved out first. The form I have shown is primarily for milk bottles; however, if this idea is 40 patentable of course I would want to try to include or cover as wide an area as possible.

It is thought that the description taken in 45 connection with the drawings will enable a clear understanding of the invention to be had. Therefore, a more lengthy description is thought unnecessary.

While the preferred embodiment of the invention has been shown and described, it is to be understood that minor changes coming within 50 the field of invention claimed may be resorted to if desired.

I claim:

1. In a rack of the class described, a pair of longitudinal side frames, forward and rear transverse plates hingedly attached at their opposite ends to the adjacent front and rear ends of said longitudinal side frames, and an inclined channel-shaped longitudinally elongated bottle support detachably connected at opposite ends to the transverse end plates. 5

2. In a rack of the class described, a pair of longitudinal side frames, forward and rear transverse plates hingedly attached at their opposite ends to the adjacent front and rear ends of said longitudinal side frames, and an inclined channel-shaped longitudinally elongated bottle support 15 detachably connected at opposite ends to the transverse end plates, one of said plates having a flange provided with upstanding detents to accommodate the channel-shaped plate. 15

3. In a rack of the class described, a pair of longitudinal side frames, forward and rear transverse plates hingedly attached at their opposite ends to the adjacent front and rear ends of said longitudinal side frames, and an inclined channel shaped longitudinally elongated bottle support 25 detachably connected at opposite ends to the transverse end plates, one of said plates having a flange provided with upstanding detents to accommodate the channel shaped plate, and the other plate having a depression forming a keeper 30 seat permitting the adjacent end of the channel shaped plate to be removably snapped therein. 30

4. A collapsible portable vending rack of the gravity feed type comprising a pair of horizontally elongated vertically disposed side frames 35 arranged in parallel relationship, forward and rear transverse end-plates hingedly attached at their opposite ends to the adjacent front and rear ends of said longitudinal side frames, one of said end plates having a horizontal flange provided with upstanding detents, the other plate having a depression forming a keeper seat, and a horizontally disposed inclined delivery plate longitudinally elongated and adapted to support a plurality of bottles, said plate being arranged 40 between the frames and one end of the plate being releasably engaged with said flange and detents, the other end of the plate being removably fitted in said keeper seat. 45

SYLVAN N. GOLDMAN.
